(57) **CLAIM**

The ornamental design for lighting fixture, as shown and described.

DESCRIPTION

FIG. 1 is a bottom perspective view of the lighting fixture of the present disclosure;

FIG. 2 is a bottom view thereof;

FIG. 3 is a top view thereof;

FIG. 4 is a left side view thereof, the right side view being a mirror image;

FIG. 5 is a front side view thereof; and,

FIG. 6 is a back side view thereof.

Those portions of the present invention which are presented in phantom illustrate the environment of the design only and form no part of the claimed design. Moreover, the shading presented in the accompanying drawings is provided merely to highlight the contour of the invention and is not intended to be illustrative of texture or gloss.
